UNITED STATES PATENT OFFICE

162,706

CONDIMENT DISPENSING CONTAINER

Jack Baron, New York, N. Y.

Application March 29, 1950, Serial No. 8,849

Term of patent 14 years

(Cl. D44—22)

To all whom it may concern:

Be it known that I, Jack Baron, a British subject and resident of the city of New York, in the State of New York, have invented certain new, original, and ornamental Design for a Condiment Dispensing Container, of which the following is a specification, reference being had to the accompanying drawing, forming a part thereof.

In the accompanying drawing:

I claim:

The ornamental design for a condiment dispensing container, as shown.

JACK BARON.
